UNITED STATES PATENT OFFICE.

SHERWOOD BRANDON BLODGETT, OF ATLANTA, GEORGIA.

MAGIC CARD-ELEVATING APPARATUS.

Application filed April 9, 1926. Serial No. 100,993.

This invention relates to magical apparatus and has special reference to a card elevating device.

More particularly the invention relates to a card elevating device by means of which selected cards may be caused to rise from a receptacle such as a tumbler or other drinking glass slowly and noiselessly.

One important object of the invention is to provide an improved and simple device of this character which can be readily dropped into any ordinary drinking glass capable of holding a pack of playing cards and which, when so positioned, may be released to act on certain of the cards and cause them to rise one by one from the glass slowly and noiselessly.

A second important object of the invention is to provide a device of this character which is compact in its nature so that it may readily be concealed in the hand of the person performing the trick.

A third important object of the invention is to provide a device of this character wherein the cards will rise slowly from the glass while the performer may be moving around the stage or room or may be standing at a distance from the glass and its pack of cards.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

40 Figure 1 is a perspective view of the device removed from the glass.

Figure 2 is a side elevation of the invention showing the same in connection with a glass and pack of cards.

45 Figure 3 is a front view of the invention.

Figure 4 is a detail section through the line 4—4 of Figure 3.

Figure 5 is a detail section on the line 5—5 of Figure 3.

50 Figure 6 is a perspective view of a modified form of the invention as positioned in a drinking glass.

Figure 7 is a perspective view of the modi-

fied form with part of the casing broken away to show the interior. 55

Figure 8 is a detail section on the line 8—8 of Figure 7.

In the first form of the invention there is provided a spring metal support 10 having at one end a hook 11 which, in use, engages the edge of a glass G. On the other end of the support 10 is a pair of spaced hinge gears 12 wherethrough passes a pintle 13. At 14 is a main frame having legs provided with hinge ears 15 engaging on the ends of the pintle 13. Coiled around the pintle between the ears 12 is a torsion spring 16 the ends of which extend outwardly to bear respectively against the support 10 and frame 14, the action of the spring being limited by a tension strand or cord 17. At the upper end of the frame 14 is a pair of forwardly extending arms 18 wherein is fixedly mounted a shaft 19 on which is revolubly mounted a pair of heads 20 carrying a cylinder 21. 70 Within the cylinder 21 is a torsion spring 22 which surrounds the shaft 19 and has one end connected to said shaft while its other end is connected to the cylinder 21. Adjacent each end of the cylinder there is provided a series of soft rubber washers 23.

In using this form of the device a pack of cards P is taken and by proper manual manipulation the cards to be elevated from the glass are positioned on top of the pack. The prepared pack is then dropped in the glass with its face toward the audience and behind the pack is placed the elevating device which has been wound up by rotating the cylinder 21 to tension the spring 22, the device being held in this wound up position by a trigger lever 24 pivoted to the frame and having an end 25 movable into and out of engagement with a lug 26 projecting from the cylinder. It is to be noted that the cylinder is preferably filled with some viscous material such as liquid glue so that, when the trigger is released the spring 22 only produces slow rotation of the cylinder 21. The device having been slipped in the glass 100 behind the cards, the top card will be pressed against by the rubber rollers 23. The trigger is now released by the operator working the same with his finger. The spring 22 revolves the cylinder and the back card will 105 rise until it is freed from the rollers 23.

whereupon the next card will rise and so on until the spring has run down. It is obvious that the number of cards to rise may be limited by having a false deck of cards 5 with most of the cards glued together.

The second form of the device illustrated in Figures 7 and 8 is very similar to this form in its general function and operation. In this second form there is provided a casing 27 consisting of a pack of cards hollowed to receive a frame 28 in the form of a box open at the upper part of one side and also at the top. The upper part of the box supports a fixed shaft 29 whereon is a cylinder 30 having a spring 31 in its interior like the spring 24. This cylinder is provided with the usual rubber rollers 32 and the casing formed between the hollowed out card pack is provided with openings 33 wherethrough 10 the rollers 32 project slightly. The cylinder is provided with a lug 34 and mounted in guides 35, on the frame 28 is a trigger rod 36 which projects through one side of the casing and carries on its inner end a finger 25 37 movable into and out of the path of the lug 34 as the rod is slid inwardly or outwardly of the casing 24.

In using this form of the invention the selected cards are palmed in a manner well known to magicians and the false pack formed by the casing 27 is substituted for the genuine pack from which the cards are selected. The selected cards are then placed with the false pack in such position that the 30 rollers 32 will act thereon. Then the false pack and selected cards are placed in the glass G and then the trigger manipulated as before.

There has thus been provided a simple and 40 efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a device of the kind described, a frame, a cylinder having a lug thereon and revolvably supported in said frame, card engaging means operating by the cylinder, means urging said cylinder to revolve in one

direction, and a releasable stop mechanism engageable with and disengageable from the lug for restraining the cylinder from movement, and releasing it from movement to move the car. 60

2. In a device of the kind described, a frame, a shaft extending transversely of and fixed in said frame, a cylinder revolvably mounted on said shaft, a torsion spring surrounding the shaft within the cylinder and having one end fixed to the shaft and the other end fixed to the cylinder, a stop lug on said cylinder, a trigger supported by the frame for movement into and out of the path of the stop lug, said engaging rollers mounted on said cylinder, and means for supporting the frame in a receptacle. 65

3. In a device of the kind described, a frame, a shaft extending transversely of and fixed in said frame, a cylinder revolvably mounted on said shaft, a torsion spring surrounding the shaft within the cylinder and having one end fixed to the shaft and the other end fixed to the cylinder, a stop lug on said cylinder, a trigger supported by the frame for movement into and out of the path of the stop lug, said engaging roller mounted on said cylinder, a C-spring having one end hinged to the bottom of the frame and its other end provided with a hook for engagement with the edge of a receptacle, and spring means at the hinged connection urging the free end of the frame away from the hook. 70

4. In a device of the kind described, a frame, a shaft extending transversely of and fixed in said frame, a cylinder revolvably mounted on said shaft, a torsion spring surrounding the shaft within the cylinder and having one end fixed to the shaft and the other end fixed to the cylinder, a stop lug on said cylinder, a trigger supported by the frame for movement into and out of the path of the stop lug, said engaging roller mounted on said cylinder, a C-spring having one end hinged to the bottom of the frame and its other end provided with a hook for engagement with the edge of a receptacle, spring means at the hinged connection urging the free end of the frame away from the hook, and flexible means connecting the frame and C-spring near the hook and arranged to limit movement of the frame away from said hook. 75

In testimony whereof I affix my signature.
SHERWOOD BRANDON BLODGETT.
